UNITED STATES PATENT OFFICE.

WILLIAM H. EBELHARE AND CLARENCE G. ARVIDSON, OF INDIANAPOLIS, INDIANA,
ASSIGNORS TO THE STENOTYPE COMPANY, OF INDIANAPOLIS, INDIANA.

STENOGRAPHIC TYPE-WRITING MACHINE.

1,252,891.

Specification of Letters Patent.

Patented Jan. 8, 1918.

Application filed November 22, 1916. Serial No. 132,845.

To all whom it may concern:

Be it known that we, WILLIAM H. EBELHARE and CLARENCE G. ARVIDSON, citizens of the United States, and residents of Indianapolis, in the county of Marion and State of Indiana, have invented certain new and useful Improvements in Stenographic Type-Writing Machines; and we do hereby declare the following to be a full, clear, and 10 exact description of the invention, such as will enable others skilled in the art to which it appertains to make and use the same.

This invention relates to improvements in typewriting machines and more particularly 15 to ribbon operating mechanism for stenographic typewriting machines,—one object of the invention being to provide simple and efficient means for feeding the inking ribbon accurately and uniformly during the manipulation of the keys.

A further object is to provide a ribbon feed mechanism in which noise will be reduced to a minimum.

With these and other objects in view, the 25 invention consists in certain novel features of construction and combinations of parts as hereinafter set forth and pointed out in the claims.

In the accompanying drawings; Figure 1 30 is a transverse view of a stenographic typewriting machine showing an embodiment of our invention; Fig. 2 is a side elevation partly in section of a portion of the machine; Fig. 3 is a transverse section through 35 one of the ribbon reels; Fig. 4 a detail view showing devices for shifting the gearing manually, and Fig. 5 is a detail view of the gear retaining means.

1 represents the main casing of the machine, and 2 an inner frame secured to the main casing by means of screws such as indicated at 3, and carrying the parts of the operating mechanism.

The specific construction of the key lever 45 and type mechanisms are not essential to an understanding of the ribbon actuating mechanism hereinafter described, but it may be here stated that key lever and type mechanisms such as disclosed in our application 50 Serial No. 125,225 may be employed. It will be understood however, that the ribbon moving mechanism is actuated from a universal bar and that the operation of the latter is controlled by the key levers.

55 Ribbon reels 4 are located above the top

of the casing 1 and the inking ribbon may pass from one of these reels to the other and past the printing means in a manner which is well understood.

The ribbon reels 4 are mounted on vertical 60 shafts 5 and the latter are provided with slots 6 which receive lugs 7 projecting from the hubs of the reels whereby the latter will be caused to rotate with the shafts. The top of the casing 1 is made with openings 8 65 through which the shafts 5 pass and bushing 9 for said shafts are disposed between the reels and the top of the inner frame 2. These bushings may rest upon spring washers 10 located upon the frame 2. Bearing 70 sleeves 11 are secured to and depend within the frame 2 for the passage of the shafts 5 and to the lower ends of the latter, immediately below the sleeves 11, horizontally disposed beveled gears 12 are secured. 75

A horizontal actuating shaft 13 is mounted near its respective ends in suitable bushings 14 carried by the side walls of the frame 2. Sleeves 15 are mounted securely to the shaft 13 which can slide and rotate in 80 bushings 14 and to the inner ends of sleeves 15 beveled pinions 15^a are secured for transmitting motion to the ribbon reel shafts 5. The two sleeves 15 are spaced on the shaft 13 by a sleeve 16, fastened securely on shaft 85 13, thus making the shaft 13 with sleeves 15 and 16, and pinions 15^a, a fixed unit which slides in the bushings 14 to cause one of the pinions to move out of mesh with its gear wheel and the other pinion to move into 90 mesh with its gear wheel. The intermediate sleeve 16 is provided centrally with an annular flange 17 having a beveled peripheral portion 18 to be engaged by the beveled teeth 19 of a retaining member 20, so as to 95 hold one or the other of the beveled pinions in mesh with its gear wheel while the other pinion is out of mesh with its gear wheel.

The retaining member 20 is pivotally mounted between the depending arms of a 100 bracket 21 secured under the top of the frame 2, and the toothed end of said retaining member is retained in operative relation to the beveled flange 17 by means of a spring 22,—the tension of which may be adjusted 105 by means of a screw 23 passing through the top of the frame 2.

The pinions on the shaft 13 may be shifted to move one of said pinions out of mesh with its gear wheel and the other pinion 110

into mesh with its gear wheel when the direction of travel of the inking ribbon is to be changed, by moving the shaft 13 which carries said pinions longitudinally in the bushings 14. This may be accomplished automatically by means of mechanism such as described in our application Serial No. 132,846 or it may be accomplished manually as disclosed in our application Serial No. 10 132,612. In order, however, that some means shall be disclosed in this application for effecting the shifting of the gearing to change the direction of travel of the inking ribbon, we have shown manually operable means for 15 this purpose. The manual shifting or ribbon reversing device shown in the drawing comprises a bifurcated arm 24 secured to the lower end of a shaft 25 and disposed to embrace the centrally located annular flange or 20 wheel 17. The shaft 25 is suitably mounted in the framework of the machine and is provided with a knurled knob 26 projecting above the framework. It is apparent that by turning this knob, the bifurcated arm 24 25 will be moved in one direction or the other, and by its co-operation with the flange or wheel 17 cause the pinions to be shifted as previously explained, to effect a reversal of the direction of the ribbon feed.

30 The rotation of the shaft 13 is effected by means of ratchet devices controlled by the movements of a universal bar 27, the latter being operated by the key levers 28. This universal bar is disposed under the key 35 levers somewhat in advance of the pivotal mountings of said levers and as provided at its respective ends with arms 29, 30 pivotally attached to the frame 2 in line with the pivotal mountings of the key levers, as fully 40 explained in our application, Serial No. 125,224. The arm 30 at one end of the universal bar is made with a finger 31 which projects upwardly beyond the pivotal support of said arm. One end of a spring 32 is 45 attached to the frame 2 and its other end is connected with the finger 31, —said spring serving to retain the universal bar and the parts actuated thereby in their normal positions and to return the same to such positions.

50 The shaft 13 is provided at one end with a shank 33 projecting beyond the adjacent bearing of said shaft in the frame 2, and on this shank, a flanged hub 34 is located. 55 A ratchet wheel 35 having fine teeth is secured to the hub 34 and both may be secured to the shank of the shaft 13 by means of a clamping nut 36 and washer 37. A plate or carrier 38 is loosely mounted on the hub 34 between the flange thereof and the ratchet wheel and carries a spring-actuated pawl 39 to engage said ratchet wheel. This plate or carrier is provided in its lower part with an elongated slot 40 to receive a pin 41 projecting laterally from an upwardly and for-

wardly projecting finger 41^a of the universal bar arm 30, —the connection between the pawl carrier 38 and the universal bar being thus located in front of the pivotal mountings of both the universal bar and the key 70 levers. Thus when a key lever is depressed, the downward movement of the universal bar will cause the plate or carrier 38 to move downwardly and the pawl 39 to propel the ratchet wheel 35 thus turning the ribbon 75 feed gearing and feeding the ribbon a short distance. A pivoted gravity dog 39^a may be provided to prevent retrograde rotation of the ratchet wheel and the shaft to which it is secured. It will be observed that the 80 inking ribbon is fed on the down stroke of a key lever and after the type has printed upon the paper and a new surface of the ribbon will be presented ready for the next impression. The ribbon spools or reels are 85 protected by means of a cover 42 mounted upon the frame or casing 1, —said cover being sustained properly spaced from the top of the casing by means of flanges 43 and posts 44, said cover being held removably in 90 place by means of knobs 45 screwed on shanks 46 of said posts.

Various slight changes might be made in the details of construction of our invention without departing from the spirit thereof or 95 limiting its scope and hence we do not wish to restrict ourselves to the precise details herein set forth.

Having fully described our invention what we claim as new and desire to secure by Letters-Patent, is:—

1. In a typewriting machine, the combination with a frame, ribbon spool shafts, an actuating shaft, gearing between said shafts, and key levers, of a universal bar under the 105 key levers and having arms pivotally attached to the frame, a ratchet wheel on the actuating shaft, a pivoted carrier, a pawl mounted on said carrier to engage the ratchet wheel, and an operating connection 110 between said carrier and one of the arms of the universal bar.

2. In a typewriting machine, the combination with ribbon spool shafts, an actuating shaft, gearing between said shafts and 115 key levers, of a spring sustained universal bar disposed under the key levers and having an arm at one end, a ratchet wheel secured to the actuating shaft, a pivoted pawl carrier, a pawl mounted on said carrier to 120 engage the ratchet wheel, and intermeshing means between said carrier and the said universal bar arm.

3. In a typewriting machine, the combination with a frame, ribbon spool shafts, an 125 actuating shaft, gearing between said shafts, and a universal bar provided with arms pivoted to the frame, of a ratchet wheel secured to the actuating shaft, a pivoted carrier, a pawl mounted on said carrier to engage the 130

ratchet wheel, and a pin-and-slot connection between said carrier and one of the universal bar arms.

4. In a typewriting machine, the combination with a frame, ribbon reel shafts, an actuating shaft, and gearing between said shafts, of a universal bar, arms at respective ends of said bar having pivotal connection with the frame, a spring attached to the frame and to one of said arms above the pivot thereof, a pin projecting laterally from one of said arms, a ratchet wheel secured to the actuating shaft, a pivotally mounted pawl carrier having an elongated slot to receive the pin on the universal bar arm, and a spring-actuated pawl mounted on the pawl carrier in position to engage said ratchet wheel.

5. In a typewriting machine, the combination with a frame, of vertical shafts, bushings for said shafts depending within said frame, ribbon reels mounted on said shafts, bushings between said reels and the frame,

springs interposed between said last-mentioned bushings and the frame, gears secured to the lower ends of said shafts, a horizontal actuating shaft, pinions on said horizontal shaft to mesh with said gears, and means for operating the actuating shaft.

6. In a typewriting machine, the combination with a frame, vertical shafts mounted therein, ribbon reels on said shafts above the frame and means for actuating said shafts, of a flanged cover inclosing said reels, posts spacing said cover from the frame, and knobs removably attached to said posts and holding said cover removably in place upon the frame.

In testimony whereof, we have signed this specification in the presence of two subscribing witnesses.

WILLIAM H. EBELHARE.
CLARENCE G. ARVIDSON.
